UNITED STATES PATENT OFFICE.

GLENN SCOTT, OF KELLETON, IOWA.

WIRE-GRIP.

1,293,559.

Specification of Letters Patent.

Patented Feb. 4, 1919.

Application filed May 19, 1917. Serial No. 169,728.

To all whom it may concern:

Be it known that I, GLENN SCOTT, a citizen of the United States, residing at Kelleton, in the county of Ringgold and State of Iowa, have invented certain new and useful Improvements in Wire-Grips, of which the following is a specification.

This invention relates to certain new and useful improvements in wire grips.

10 The principal object of the invention is to provide a simple form of grip or clamp which can be readily attached to a wire and will firmly hold the same while being stretched, the parts of the clamp being so arranged that the wire may be readily disconnected therefrom when desired.

Another object is to provide a clamp having coacting parts between which the wire is received, the gripping action of said parts 20 being increased in proportion to the strain exerted on the wire during the operation of stretching the same.

The above and other objects and advantages of this invention will be in part described and in part understood from the following description of the present preferred embodiment, the same being illustrated in the accompanying drawings in which,

30 Figure 1 is a side elevation of my improved invention.

Fig. 2 is a sectional view taken on line 2—2 of Fig. 1.

In the drawings wherein is illustrated the 35 preferred embodiment of my invention, the numeral 1 designates a conical bar or body portion which is substantially circular in cross section and has an opening extending transversely through the reduced end 2 thereof. Pivots mounted in said opening 40 are a ring 3 having a snap hook 4 integrally associated therewith and adapted to be engaged with a chain or other pulling appliance as indicated at 5.

Slidably mounted on the cone shaped member 1 is a split ring 6 which is preferably made rounded in cross section to present a smooth gripping surface to the wire. The inside diameter of the ring 6 is less than the diameter of the larger end of the member 1. 50 The ring is prevented from slipping off on the reduced end of the body portion by means of the ring 3.

In operation, the ring 6 is first moved in the direction of the ring 3, and the wire to 55 be stretched, as indicated at 7, is laid lengthwise on the member 1. The split ring is then moved toward the larger end of the body portion 1 until the wire is clamped between said ring and body portion in the manner 60 shown in Fig. 1. The snap hook 4 is then connected to a chain or the like as indicated at 5 which may be tightened with any suitable form of wire stretcher.

The construction herein shown and described represent the preferred embodiment of my invention but I desire to be understood that I do not limit myself to the same but may resort to such changes in construction and arrangement of the parts as may 70 come within the scope of the invention, without departing from the spirit of the same.

I claim:

A wire grip, including a tapering conical body portion having an opening extending 70 through the smaller end thereof, a ring pivotally secured in said opening, a snap hook carried by said ring and adapted to be coupled with a wire stretcher and a split ring 75 slidably mounted on said body portion. 80

In testimony whereof I affix my signature in presence of two witnesses.

GLENN SCOTT.
